UNITED STATES PATENT OFFICE.

ARTHUR R. DARLING, OF INDIANAPOLIS, INDIANA, ASSIGNOR TO EDWARDS INSTRUMENT COMPANY, OF INDIANAPOLIS, INDIANA, A CORPORATION OF INDIANA.

HOLDER FOR HIGH-TENSION ELECTRODES.

1,078,597.

Specification of Letters Patent.

Patented Nov. 11, 1913.

Application filed January 6, 1913. Serial No. 740,272.

To all whom it may concern:

Be it known that I, ARTHUR R. DARLING, a citizen of the United States, residing at Indianapolis, in the county of Marion and State of Indiana, have invented a new and useful Holder for High-Tension Electrodes, of which the following is a specification.

It is the object of my invention to provide a safe and convenient holder for high tension electrodes, such as are used for medical treatments with Tesla currents, whereby the operator is entirely protected and the patient is protected against accidental metallic contacts.

In carrying out my invention, I provide a holder comprising inner and outer insulating members separated by an air space, and a connecting socket within the inner member, the socket and the inner member being open at one end for the insertion of the high tension electrode, and the socket being connected with the high tension source by a conductor passing out the other end of the inner insulating member.

The accompanying drawing illustrates my invention.

Figure 1 is a longitudinal central section, with parts of the end plugs in elevation, through an insulating holder embodying my invention, showing in dotted lines an associated high tension electrode of one form; and Fig. 2 is a perspective view, partly in section, showing the construction and mounting of the metal socket within the inner insulating member.

There is an inner insulating tube composed of two partly telescoped portions 10 and 11 which have a driving fit upon each other or are otherwise fastened together, the tube 11 being slightly the larger. An outer insulating tube 12, concentric with the inner one, is separated from the latter by an air space 13, containing air at normal pressure, the lower end of the tube 10 being spaced from the outer tube 12 by a collar 14 which may be either integral with or a separate piece from the tube 10. Fitted in the upper and lower ends of the outer tube 12 are two end plugs 15 and 16, which preferably have a driving fit in such tube though they may also be glued or otherwise fastened in place if desired. The tube 11 projects out through the end plug 15 and some distance beyond it, and is open at its outer end to receive

55 the butt of a high tension electrode 17, which

butt fits into a metallic socket in the lower end of the tube 11. This metallic socket comprises a tube 18 divided except at its lower end into a number of segments by saw cuts 19. The lower end of this tube 18 has a 60 tight driving fit into the upper end of the tube 10. A metal plug 20 has a tight fit in the lower end of the tube 18, in which it may be soldered if desired, such plug having a central aperture in which is soldered 65 the bare end 21 of an insulated flexible conductor 22 extending downward through the tube 10 and a suitable opening in the end plug for connection to the Tesla coil or other source of current.

In operation, the operator grasps the outer tube 12, the high tension electrode 17 being inserted in the open projecting end of the tube 11 and the socket formed by the split tube 18. The Tesla coil or other source 75 of current being set in operation, the electrode 17 may be manipulated over the desired parts of the patient's body, without danger that the patient will come into contact with any of the metal parts connected 80 with the Tesla coil and without danger that the operator will receive any current whatever, the inner and outer tubes with the intervening air space 13 serving as an effective insulator. By thus preventing loss of current 85 to the operator, more current is rendered available for application to the patient, and this with perfect safety to the patient.

I claim as my invention:

1. A holder for high tension electrodes, comprising inner and outer members of insulating material separated by a space filled with fluid under comparatively high pressure as compared with the pressure in the 95 electrode, the inner member being open at one end to receive a high tension electrode, a socket located within the inner member and spaced from the ends thereof, and a conductor leading from said socket through the 100 opposite end of the inner member from that which receives the high tension electrode.

2. A holder for high tension electrodes, comprising inner and outer members of insulating material separated by a space, the 105 inner member being open at one end to receive a high tension electrode, a socket located within the inner member and spaced from the ends thereof, and a conductor leading from said socket through the oppo. 110

site end of the inner member from that which receives the high tension electrode.

3. A holder for high tension electrodes, comprising inner and outer members of insulating material separated by a space filled with fluid under comparatively high pressure as compared with the pressure in the electrode, the inner member being open at one end to receive a high tension electrode, a 10 socket located within the inner member, and a conductor leading from said socket through the opposite end of the inner member from that which receives the high tension electrode.

15 4. A holder for high tension electrodes, comprising inner and outer members of insulating material separated by a space, the inner member being open at one end to receive a high tension electrode, a socket located within the inner member, and a conductor leading from said socket through the opposite end of the inner member from that which receives the high tension electrode.

20 5. A holder for high tension electrodes, comprising inner and outer members of insulating material separated by a space, the inner member being open at one end to receive a high tension electrode, a socket located within the inner member, and a conductor for connecting said socket to a high 25 tension source.

25 6. A holder for high tension electrodes, comprising an outer tube, an inner tube within and spaced from the outer tube and composed of two parts of different size of which the larger fits tightly over the smaller, a metal socket fitted within the smaller part of the inner tube where such smaller part fits into the larger part, said socket extending 30 from the smaller part of the inner tube within and along the larger part thereof, said larger part of the inner tube being open at the end remote from the smaller part to receive a high tension electrode, and a conductor connected to said socket and extending out through the smaller part of the inner tube.

35 7. A holder for high tension electrodes, comprising inner and outer members of insulating material separated by a space, the inner member being open at one end to receive a high tension electrode, a socket located within the inner member, and a conductor leading from said socket through 40 the opposite end of the inner member from that which receives the high tension electrode, said inner member projecting beyond the outer member at the end which receives the high tension electrode.

45 8. A holder for high tension electrodes, comprising inner and outer members of insulating material separated by a space, the inner member being open at one end to re-

ceive a high tension electrode, and a conducting member located within and spaced 50 from the ends of the inner member and provided with means for connecting it to a high tension source, said conducting member being in proximity to the high tension electrode when the latter is inserted in the 55 open end of the inner member.

9. A holder for high tension electrodes, comprising inner and outer members of insulating material separated by a space, the inner member being open at one end to receive a high tension electrode, and a conducting member located within the inner member and provided with means for connecting it to a high tension source, said conducting member being in proximity to the 65 high tension electrode when the latter is inserted in the open end of the inner member.

10. A holder for high tension electrodes, comprising a member of insulating material open at one end to receive a high tension electrode, a conducting member within 70 said member of insulating material and in proximity to the high tension electrode when the latter is placed in said open end of the member of insulating material, and a conductor leading from said conducting member out of the opposite end of the member of insulating material from that which receives the high tension electrode.

11. A holder for high tension electrodes, comprising a member of insulating material open at one end to receive a high tension electrode, a conducting member within said member of insulating material and in proximity to the high tension electrode when the latter is placed in said open end of the member of insulating material, said conducting member being spaced from all exposed surfaces of said member of insulating material, and a conductor leading from said conducting member out of the opposite end of the member of insulating material from that which receives the high tension electrode.

12. A holder for high tension electrodes, comprising spaced inner and outer members of insulating material, the inner member being open at one end to receive a high tension electrode, and a conductor leading into 100 the opposite end of the inner member from that which receives the high tension electrode.

In witness whereof, I have hereunto set my hand at Indianapolis, Indiana, this 3rd day of January, A. D. one thousand nine hundred and thirteen.

ARTHUR R. DARLING.
